(57) **CLAIM**

I claim the ornamental design for a data transmission device, as shown and described.

DESCRIPTION

FIG. 1 is a top plan view of a data transmission device; FIG. 2 is a perspective view of a data transmission device; FIG. 3 is a second perspective view of a data transmission device; FIG. 4 is a right side elevation view of a data transmission device; FIG. 5 is a left side elevation view of a data transmission device; FIG. 6 is a front elevation view of a data transmission device; and, FIG. 7 is a rear elevation view of a data transmission device. The bottom of a data transmission device, not shown, forms no part of the claimed design. Broken line areas show environmental subject matter and form no part of the claimed design.

1 Claim, 7 Drawing Sheets
